SHEET ALIGNING AND GAUGING DEVICE

David M. Scoville, San Francisco, Calif.

Application May 15, 1936, Serial No. 79,944

2 Claims. (Cl. 282—29)

My invention relates to improvements in sheet aligning and gauging devices for aligning and preserving such an alignment of a plurality of sheets for insertion into a typewriter and operates in conjunction with improved means for aligning said sheets along an adjacent edge or laterally to the first alignment and for indicating or gauging the position of the bottom of said aligned sheets relatively to the writing line of a typewriter in order that an operator may readily determine when the said lower edge or bottom of said sheets is approaching said writing line.

The primary object of the present invention is to provide a new and improved device for aligning a plurality of superimposed sheets for insertion into a typewriter.

Another object is to provide a new and improved device of the character described having improved means for indicating to an operator of a typewriter within which a plurality or a single sheet is inserted, the position of the bottom of said sheet or sheets relatively to the writing line of a typewriter, in order that a neat and proper bottom and side margins may be obtained.

I accomplish these and other objects by means of the improved device disclosed in the drawing forming a part of the present application, and in which—

Fig. 1 is an elevation of my improved device; Fig. 2 is a similar view of the same folded to align a plurality of superimposed sheets;

Fig. 3 is a side elevation of Fig. 2, with the thickness of the sheets greatly exaggerated;

Fig. 4 is a broken view of a portion of a typewriter platen disclosing one application of my improvement; and

Fig. 5 is an end elevation of a platen, showing another application of the improvement.

Referring to the drawing:

The numeral 1 is used to designate a sheet scored parallel to one end thereof as at 2 to form a tab 3 foldable upon said sheet 1 to form a pocket 4 to receive and align the ends of a plurality of superimposed sheets 6, such as carbons and second sheets to receive impressions of matter impressed upon the top sheet.

My invention provides a second tab 7 preferably along the remote half of an edge adjacent the first end, said tab 7 being scored along its edge as at 8 so that said tab 7 may be folded upon the sheet 1 to form a second pocket to receive and align adjacent edges of said superimposed sheets 6 laterally to the first alignment of the pocket 4, to more perfectly register said superimposed sheets, one upon another.

This superimposed registration or alignment of the sheets 6 is provided to facilitate insertion of said sheets, by means of the sheet 1 and its tabs 3 and 7, into a typewriter. The sheet 1 is provided preferably along the left margin thereof with indices 9 which indices are offset at approximately midposition of the sheet and onto the face of the tab 7 as at 11, so that after the sheet 1 with its aligned sheets 6 is inserted into a typewriter and rolled around the platen 12 thereof and said tab 7 unfolded, the said indices 11 will appear immediately adjacent the left edges of said aligned sheets 6 to indicate to an operator the position of the bottom of said aligned sheets 6 relatively to the writing line of said typewriter, not shown, as indicated by the usual scale 14, as disclosed in Fig. 4 of the drawing.

The tab 7 is bevelled on its end nearest the tab 3 as at 15, the purpose of which will herein-after be more fully set forth.

In operation:

The superimposed sheets 6 are inserted with one set of ends in the pocket 4 and said edges shogged into alignment within said pocket. The tab 7 is then folded over said sheets 6 and the edges of said superimposed sheets adjacent the first aligned edges are shogged into alignment against said tab 7 and laterally to the first alignment within the pocket 4 so that said superimposed sheets 6 are in substantially perfect superimposed alignment.

The sheet 1 with its aligned sheets 6 is then grasped by holding the tabs 3 and 7 and inserted into a typewriter, not shown, by inserting the end of the sheet 1 with the tab 3 thereon foremost and between the platen 12 and paper rest 16 of a typewriter and the platen is then turned in the usual manner to bring the aligned sheets 6 into writing position. When the tab 7 is released, the presence of the superimposed sheets 6 as well as the normal tendency of the tab 7 to unfold will cause said tab to assume a slightly more than right angle to the body of the sheet 1, as disclosed in Fig. 5 of the drawing. As the sheet 1 with its superimposed sheets 6 are fed further into the typewriter in the course of writing, the bevelled end 15 of the said tab 7, when it encounters the curved edge of the paper rest 16, will be fully unfolded by said curved end so that the indices 11 on the face of said tab 7 will be presented to the view of an operator, when slightly more than half of the sheets 6 have been filled. These indices will then indicate to an operator the position of the bottom of the superimposed sheets 6 relatively to the

writing line of the typewriter as indicated by the scale 14, as fully disclosed in Fig. 4 of the drawing. By means of this arrangement a neat margin may be preserved for the bottom as well as 5 the left hand side of the superimposed sheets.

The bevelled end 15 of the tab 7 will operate similarly when encountering the supporting arm of the paper holders or any other obstruction which may be encountered during its progress 10 through the machine.

Having described my invention I claim—

1. The combination with a sheet aligning device, comprising a sheet folded upon itself at one end to form a pocket for receiving and aligning one set of edges of a plurality of superimposed sheets of a tab formed integral with the remote half of an edge adjacent to said end, said tab being foldable upon said sheet to form a second pocket to receive and align adjacent edges 15 of said superimposed sheets laterally to the first alignment and to facilitate preservation of both alignments and insertion of said aligned sheets into a typewriter, said tab being provided with indices upon its face to indicate the position of 20 the bottom of said superimposed sheets rela-

tively to the writing line of a typewriter when said superimposed and aligned sheets are inserted therein.

2. The combination with a sheet aligning device, comprising a sheet of foldable material 5 folded upon itself at one end to form a pocket for receiving and aligning the ends of a plurality of superimposed sheets, of a tab formed upon the remote portion of an edge adjacent said end and folded upon said sheet to form a second 10 pocket for aligning adjacent edges of said superimposed sheets, laterally to the first alignment, said tab being provided with indices upon its face to indicate the relative position of the said superimposed sheets relatively to the writing line 15 of a typewriter when said sheets and aligning device are inserted therein, said tab having a bevelled end adjacent the folded end of said sheet by means of which said tab may be unfolded when moving over the edge of a paper 20 rest of a typewriter within which said superimposed sheets are inserted to display said indices when said sheets are moved into said typewriter and around the platen thereof.
